UNITED STATES PATENT OFFICE.

JOSEPH L. SILSBEE, OF CHICAGO, ILLINOIS.

RAILWAY ROAD-BED.

SPECIFICATION forming part of Letters Patent No. 793,163, dated June 27, 1905.

Application filed April 29, 1904. Serial No. 205,510.

To all whom it may concern:

Be it known that I, JOSEPH L. SILSBEE, a citizen of the United States, residing at Chicago, in the county of Cook and State of Illinois, have invented certain new and useful Improvements in Railway Road-Beds, of which the following is a specification.

The principal object of this invention is to provide a simple, economical, and efficient road-bed formed of concrete or similar material reinforced throughout the mass and external thereof, as will more fully hereinafter appear. Other and further objects of the invention will appear from an examination of the drawings and the following description and claims.

The invention consists principally in a railway road - bed formed of continuous strips of concrete or similar material tied or joined together transversely, reinforcing metallic members extending longitudinally through the mass, and railway-rails laid on top of the strips of concrete and secured to the internal metallic members, so as to form a truss in connection therewith.

The invention consists, further and finally, in the features, combinations, and details of construction hereinafter described and claimed.

In the accompanying drawings, Figure 1 is a plan view of a portion of a railway - bed looking at it from above and with the rails removed; Fig. 2, a side sectional elevation of the same, showing the railway-rails in position, taken on line 2 of Fig. 1; Fig. 3, a transverse sectional view taken on line 3 of Fig. 1 looking in the direction of the arrow; Fig. 4, an enlarged sectional detail of the rail and securing mechanism; Fig. 5, an enlarged sectional detail taken on line 5 of Fig. 2, and Fig. 6 a sectional elevation taken on line 6 of Fig. 5.

In the art to which this invention relates it is well known that it is very desirable in many instances to dispense with the usual railway ties and sleepers and to provide an economical and efficient substitute therefor. To accomplish this object, this invention is principally designed.

In constructing a railway road-bed in ac-

cordance with these improvements I provide two continuous strips formed of concrete *a a*, joined together at a plurality of points by transverse connecting - bonds *b b*, also made from concrete or similar material and forming a frame - platform. These strips, with their transverse connecting - bonds, preferably provide central elongated openings of any desired length, which when the road is in use may be filled with ordinary ballasting material. By this arrangement the ordinary sleepers or ties are dispensed with. It is very desirable, however, to strengthen the mass of concrete which forms this frame-platform internally and externally—in other words, to truss it, so as to assist in resisting the stress and strains incident to the use thereof. In order so to do, the longitudinal strips of concrete are provided with longitudinally-extending metal rods or strips *c*, extending longitudinally through the mass from points near the lower surface of the concrete to points above the upper surface thereof, as shown particularly in Fig. 6. The railway-rails *d* are then provided and laid directly on the concrete or in some instances may be laid upon wooden blocks or strips *e*. The upper parts of these longitudinal metal members *c* are looped, as at *f*, and these loops are arranged in parallel lines and in staggered relation with each other, as shown particularly in Fig. 1. Between these parallel lines of loops the rails are laid and upon the blocks, as above stated.

The rails are fastened down in position by means of curved wedges *g*, the lower surface of which is provided with serrations or teeth *h*, adapted to engage with a serrated block *i*, secured to the mass of concrete. When the rails are laid in position and secured to the loops, as above stated, they form in connection with the embedded longitudinal metal members a truss, which assists the mass of concrete in resisting the stress and strains incident to the use of a railway road-bed, all of which will be understood and appreciated by those skilled in the art.

I claim—

1. In a railway road-bed of the class described, the combination of a plurality of con-

tinuous strips of concrete or similar material, metal members extending longitudinally through the mass, railway-rails laid longitudinally upon the upper surface of such concrete strips, and means securing the railway-rails to the metallic embedded strips so as to form a truss in connection therewith, substantially as described.

2. In a railway road-bed of the class described, the combination of a plurality of continuous strips of concrete or similar material, metal members extending longitudinally through the mass, railway-rails laid longitudinally upon the upper surface of such concrete strips, and U-shaped members for securing the railway-rails to the embedded strips, substantially as described.

3. In a railway road-bed of the class described, the combination of a pair of strips of concrete or similar material longitudinally arranged and bonded together transversely at a plurality of points, metallic members longitudinally arranged in the mass of said cement and having U-shaped portions extending up through the upper surface thereof,

railway-rails laid upon the upper surface of such strips of cement, and wedge members for securing the base-flanges of the railway-rails to the U-shaped projecting portions, the whole forming a truss structure, substantially as described.

4. In a railway road-bed of the class described, the combination of a pair of strips of concrete or similar material longitudinally arranged and bonded together at a plurality of transverse points, a pair of parallel-arranged metal members embedded in each of the longitudinal concrete strips and provided with U-shaped upwardly-extending portions arranged in staggered relation, railway-rails laid between the parallel-arranged metallic members and on the upper portion of the concrete strips, and wedge members for securing the railway-rails to the U-shaped projecting portions, the whole forming a trussed structure, substantially as described.

JOSEPH L. SILSBEE.
